(57) **CLAIM**

The ornamental design for a container with base and actuator, as shown and described.

DESCRIPTION

FIG. 1 is an isometric view of a top, front, and right side of an ornamental design for a container with base and actuator; FIG. 2 is a front elevational view of the container with base and actuator of FIG. 1;

FIG. 3 is a rear elevational view of the container with base and actuator of FIG. 1;

FIG. 4 is a right side elevational view of the container with base and actuator of FIG. 1;

FIG. 5 is a left side elevational view of the container with base and actuator of FIG. 1;

FIG. 6 is a top plan view of the container with base and actuator of FIG. 1;

FIG. 7 is an isometric view of a top, front, and right side of another ornamental design for a container with base and actuator;

FIG. 8 is a front elevational view of the container with base and actuator of FIG. 7;

FIG. 9 is a rear elevational view of the container with base and actuator of FIG. 7;

FIG. 10 is a right side elevational view of the container with base and actuator of FIG. 7;

FIG. 11 is a left side elevational view of the container with base and actuator of FIG. 7; and,

FIG. 12 is a top plan view of the container with base and actuator of FIG. 7.

The dash-dash-dash broken lines are included for the purpose of illustrating portions that form no part of the claimed design.
